UNITED STATES PATENT OFFICE

1,926,277

HYDRAULIC POWER TRANSMITTER

James Fraser and Duncan Campbell, Glasgow,
ScotlandApplication April 29, 1931, Serial No. 533,858,
and in Great Britain July 16, 1930

1 Claim. (Cl. 60—54)

The present invention relates to gearless power transmissions and more particularly to that class in which a driving member consisting of a turbine hereinafter referred to as the impeller is employed to accelerate and maintain in circulation in a closed circuit a liquid which in turn strikes against the vanes or blades of a reaction turbine attached to the driven shaft—imparting thereto a rotary motion.

The present invention relates to an improved hydraulic power transmitter and has for its object to so construct such transmitter as to be suitable for all conditions of application, but more particularly in its application to motor cars and such like vehicles, marine propulsion electric motors and any other means of power transmission.

The invention also has for an object to provide certain improved detail constructions wherein the device is relatively compact and simple in construction, and wherein the desired strength may be conserved with respect to the various operating parts.

With the foregoing and other objects in view, the invention will be more fully described hereinafter, and will be more particularly pointed out in the claim appended hereto.

In the drawing, wherein like symbols refer to like or corresponding parts throughout the several views.

Figure 1 is a sectional elevation of the apparatus illustrating our invention.

Figure 2 is an end view of Figure 1 with part in section.

Figure 3 is a diagrammatic view showing the relative positions of the propeller vanes or blades in the impeller.

Figure 4 is a fragmentary enlarged section through the device, showing the pitot tube for discharging fluid from the gear circuit, and

Figure 5 is a like view showing the pitot tube for supplying the fluid to the circuit.

Referring to the drawing, H is the outer casing of turbine transmitter on the engine side and I the outer casing on the driven side, C being the driving shaft connected to engine and on which shaft is keyed the impeller turbine B but which is able to slide axially on this shaft C by means of the forked lever J fixed to the operating spindle K, any suitable mechanical arrangement controlled by the driver being employed for this purpose.

The impeller turbine B has its vanes or blades A so formed and disposed at or near the periphery that the direction of discharge there-

from forms an acute angle *a* with the tangent *b* at point of exit *c*, see Figure 3, radial division-plates B' being also provided near the center of the impeller turbine B, and which impeller blades are in direct line radially with the vanes 60 or blades D of the ahead driven turbine as shown in Figure 1, L being the connecting channel to the return conduit M. The turbine blades D are suitably fixed to, or are integral with the driven disc F, which disc F is suitably attached to the 65 driven shaft N. The reversing turbine blades E are also attached to, or are integral with the driven disc F and are in the same plane axially with the ahead turbine vanes or blades D, but are disposed outside the stationary vanes or blades 70 G, said vanes or blades G being attached to the fixed disc O. To reverse the driven shaft N, the impeller B is moved along the driving shaft C by means of the operating spindle K, and forked lever 75 J by any suitable means, until the blades A are radially in line with the stationary blades G and reverse turbine blades E, P being the connecting channel with these to return conduit M. The disc O is suitably attached to the disc Q, this disc 80 Q having suitable holes or passages at its inner diameter, in line with the entrance to the impeller B, and the return conduit M. The inner walls of the conduit M are formed by the inner piece R, which may be integral with the outer 85 casing H, or held in position by the distance pieces S. Fluid for supplying the working chamber is provided by means of the pitot tube T, or tubes in the conduit M so that their outlet faces in the direction of flow of fluid, or discharge of fluid 90 can be obtained by pitot tubes whose inlets face the direction of flow of fluid as per arrows *a'*, see Figures 4 and 5.

The disc Q as shown in Figure 1 is fixed to the inner wall R and is centrally perforated to receive the hub of the impeller turbine B, and provides a fixed bearing or support for the same. This disc Q is likewise cut or cored out adjacent its inner central portion to permit a limited movement of the impeller turbine B when the 100 same is shifted to the left as shown to reverse the action of the mechanism.

It will be obvious that various changes in the construction, combination and arrangement of parts could be made which could be used without departing from the spirit of our invention and we do not mean to limit the invention to such details except as particularly pointed out in the claim.

Having thus described our invention, what we 110

claim and desire to secure by Letters Patent of the United States is:

In a hydraulic power transmitter, a casing, a driving shaft mounted co-axially in the casing, 5 a driven shaft disposed co-axially in the casing, an impeller turbine slidably mounted on the driving shaft and disposed in the casing, an outer disc housed in the casing and connected to the driven shaft, co-operating blades on the impeller 10 turbine and on said disc for effecting a relative turning movement between the same in one direction, means for shifting the impeller turbine on the driving shaft, a second set of blades mounted

on said outer disc, a fixed disc centrally located in the casing adapted to have its inner portion cut away to provide a bearing for the impeller turbine and limit the sliding movement of the same and reversing blades mounted on the fixed disc in register with said second set of blades of the outer disc and adapted to register with the blades of the impeller turbine when shifted to reverse the direction of relative turning between the outer disc and the impeller turbine.
